UNITED STATES PATENT OFFICE.

CALVIN B. PATCH, OF GLENELLYN, ILLINOIS, ASSIGNOR TO WILLIAM H. MINER, OF CHAZY, NEW YORK.

ROLLER SIDE BEARING.

1,156,094.

Specification of Letters Patent. Patented Oct. 12, 1915.

Application filed October 8, 1914. Serial No. 865,813.

To all whom it may concern:

Be it known that I, CALVIN B. PATCH, a citizen of the United States, residing at Glenellyn, in the county of DuPage and 5 State of Illinois, have invented a certain new and useful Improvement in Roller Side Bearings, of which the following is a full, clear, concise, and exact description, reference being had to the accompanying drawings, forming a part of this specification.

This invention relates to improvements in roller side bearings.

The object of the invention is to provide a roller side bearing for railway cars of 15 cheap construction wherein means are provided for automatically returning the anti-friction roller to central or normal position each time after it has served its function as an anti-friction bearing between the car 20 bolsters.

In the drawing forming a part of this specification, Figure 1 is an elevation of body and truck bolsters of a railway car showing my improved construction applied 25 thereto. Fig. 2 is a top plan view of the improved roller bearing member. Fig. 3 is a vertical sectional view taken substantially on the line 3—3 of Fig. 2. Fig. 4 is another vertical sectional view at right angles to 30 that shown in Fig. 3 and taken on the line 4—4 of Fig. 3. Fig. 5 is an end elevation of another form of roller bearing and Fig. 6 is a vertical sectional view of the structure shown in Fig. 5 and taken on the line 35 5—5 of the latter, parts of the bolsters being shown in sections in each of Figs. 5 and 6.

Referring now to Figs. 1 to 4 inclusive, 10 denotes the body bolster and 11 the truck bolster of a railway car swiveled at the center and provided with my improved bearings on each side of the center. As shown, the body bolster is provided with an integral depending bearing plate 12 and the truck bolster has secured thereto my improved 45 bearing member designated generally by the reference A. Each bearing member A, as shown, preferably comprises a bearing plate 13 riveted or otherwise suitably secured to the truck bolster, the bearing plate 13 having spaced upstanding arms 14, 14 at each corner thereof, each pair of arms 14 on the inner and outer sides of the plate having in integral fixed tread surface 15 extending therebetween. The plate 13, between the 55 tread surfaces 15, 15 is cut away as indicated

at 16 in Fig. 4 to provide the necessary clearance for an anti-friction roller 17, the latter having trunnions of reduced diameter on each side thereof, the trunnions 18, 18 being formed integrally and preferably constituting the ends of a short case hardened steel shaft extending through the roller. Each of the tread surfaces 15 is provided with a centrally located, longitudinally extending narrow slot 19 in which is reciprocatingly mounted a movable centering plate 20 having oppositely inclined upper tread surfaces 21, each plate 20 being limited in its upward movement by means of a pin and slot connection 22. Each plate 20 is normally pressed upwardly so as to have the tread surfaces 21 thereof in a plane above the tread surfaces 15, by coil springs 23, 23 seated in suitable sockets 24 in the bearing plate 13. The springs are held up at their 60 lower ends by means of tapered blocks 25 inserted from the under side of the plate 13. Between each pair of upstanding arms 14, 14 extends a more or less flexible retaining clip or bar 26 to prevent the roller 17 from 65 becoming displaced.

Under normal conditions, the plates 20 elevate the roller 17 by engaging the trunnions 18, 18 thereof to the position shown in Figs. 3 and 4. When the ends of the 70 body bolster and truck bolster approach each other, the roller 17 will be depressed and the plates 20, 20 forced into their recesses 19 until the trunnions are brought 75 into engagement with the fixed tread surfaces 15, 15, the pressure being transmitted through the latter to the truck bolster. On account of the reduced diameters of the 80 trunnions, it is apparent that the amount of surface travel of the same is much less than the surface travel of the anti-friction roller 17 when the latter is caused to rotate due to the relative swinging movement of the bolsters, which is a desirable feature in 85 that it reduces the wear. After the roller has been rotated off to one side of its normal 90 position and released, the plates 20, 20 will be lifted upwardly and the roller returned to its central normal position since the trunnions 18 will roll down the inclined tread 95 surfaces 21, 21 under the influence of gravity, thus insuring the proper positioning of the roller at all times.

In Figs. 5 and 6, the bearing plate, anti-friction roller, trunnions, fixed tread sur- 100 105 110

faces and retaining bars are or may be of the same construction as those shown in Figs. 1 to 4 and previously described. Instead of employing coil springs for actuating the movable reciprocating plates 121 for centering the roller, reversely curved leaf springs 122 are employed seated in the same elongated recesses 119 as those in which the plates 121 reciprocate.

10 Although I have herein described in detail structures embodying my invention, the same are merely illustrative and I do not wish to be limited to the details shown and described inasmuch as I am aware that 15 changes and modifications may be made without departing from the spirit of the invention.

I claim:

1. In a roller side bearing, a bearing plate 20 having fixed tread surfaces, an anti-friction roller mounted on said plate and having trunnions of reduced diameter adapted to bear and roll on said tread surfaces, and compressible centering plates for said roller engaging the trunnions thereof, said plates having inclined tread surfaces.

2. In a roller side bearing for railway cars, a bearing member adapted to be secured to a truck and having a fixed tread surface, an anti-friction roller bodily movably mounted on said bearing plate, and a movable tread surface mounted on said bearing plate having inclined tread surfaces normally holding said roller out of engagement with the fixed tread surface and adapted to be depressed to permit the roller to engage the tread surface.

3. In a roller side bearing for railway cars, a bearing plate having parallel, spaced fixed tread surfaces, a roller mounted between said tread surfaces and having trunnions of reduced diameter extending from the sides thereof, and a movable plate mounted in each of said tread surfaces, said plates being spring controlled and normally 45 lifting said trunnions out of engagement with the fixed tread surfaces.

4. In a roller side bearing for railway cars, the combination with a bearing plate having fixed tread surfaces, an anti-friction 50 roller having trunnions adapted to bear on said fixed surfaces, and movable tread surfaces engaging said trunnions and adapted to elevate the latter, under normal conditions, from engagement with the fixed tread 55 surfaces.

5. In a roller side bearing for railway cars, a bearing plate adapted to be secured to a bolster and having spaced, parallel fixed tread surfaces, an anti-friction roller 60 having trunnions adapted to engage and bear on said tread surfaces, a movable plate associated with each of said fixed tread surfaces and adapted to engage the trunnions, each of said plates having inclined tread surfaces 65 to thereby return the roller to its normal central position, means for preventing accidental removal of the roller from the bearing plate, and springs actuating said movable plates.

CALVIN B. PATCH.
